UNITED STATES PATENT OFFICE.

SAMUEL E. STIMSON, OF NEW YORK, N. Y.

COIN-CONTROLLED PASSAGE-CLOSING DEVICE.

SPECIFICATION forming part of Letters Patent No. 663,985, dated December 18, 1900.

Application filed December 16, 1899. Serial No. 740,513. (No model.)

To all whom it may concern:

Be it known that I, SAMUEL E. STIMSON, a citizen of the United States, and a resident of the borough of Brooklyn, in the city of New York, county of Kings, and State of New York, have invented certain new and useful Improvements in Mechanism for Locking and Controlling the Movements of Passage-Way-Closing Devices, of which the following is a specification.

My invention is designed for use in connection with any of the various forms of device that are employed to close passage-ways while yet permitting of the passing of persons through the latter in one or the other direction when desired, whether constructed in the form of doors, gates, or turnstiles; and it is in connection with that form of this last-mentioned device which is shown and described in my Patent No. 640,827, granted January 9, 1900, that I have illustrated my invention as applied, although it is to be understood that it is not restricted thereto.

When used in connection with a passage-way-closing device, my invention may be located at any convenient position with respect thereto, its exact location being in no sense essential so long as it co-operates with the passage-way-closing device in the accomplishment of the desired results, the object of the invention being more particularly to provide simple and convenient means whereby not only the locking of a passage-way-closing device in a position extending across the passage-way may be effected in a positive manner and the unlocking of the same permitted when it is desired to swing the device therefrom by the deposition of a coin or other token in a suitable slot or receptacle provided to receive it, but the assorting of the coins or tokens thus deposited, when of different denominations or forms, may be accomplished.

To these ends the invention consists, first, in the employment, in connection with a passage-way-closing device, of locking devices for positively locking it in a position when extending across the passage-way with mechanism that is adapted to be operated upon by a coin or other token for unlocking such closing device when required to permit of its withdrawal from across the same; second, in the

employment, in connection with the passage-way-closing device and the mechanism for locking the same in a position extending across the passage-way, of a series of levers operated by coins or tokens, a series of slots or receptacles in which such coins or tokens may be severally deposited, and a series of receptacles for receiving the respective coins or tokens after they have operated upon the levers to effect the unlocking of the closing device, and, third, in various other constructions and combinations of parts, all as will hereinafter more fully appear.

Referring to the accompanying drawings, which form a part of this specification, Figure 1 is a plan view of a passage-way-closing device with my invention applied in connection therewith; Fig. 2, a side elevation thereof with the case or housings for the stopping, controlling, and registering mechanism, a portion of the supporting shaft or axis of the passage-way-closing device, and the stand for supporting such shaft or axis shown in longitudinal vertical section; Fig. 3, a transverse sectional elevation of the passage-way-closing device with the mechanism constituting my invention and the opposite wall of the passage-way taken in the line xx of Fig. 2; Fig. 4, a plan of the stop-wheel for the passage-way-closing device, a portion of the gear through which it is connected with the shaft or axis of such closing device, and the guard or baffle lever for controlling the engagement of the locking-bar with the teeth of the locking-wheel detached; Fig. 5, a detail side and end elevation of the coin or token operated and intermediate levers, respectively, through which the operation of the guard or baffle lever is effected, with a portion of the casing or housing shown in section, and the hangers, through which the first-mentioned levers are supported therefrom, displayed in front elevation; Fig. 6, an isometric projection of the locking-bar, by means of which the locking-wheel and through it the passage-way-closing device is positively locked in the required position; Fig. 7, a plan of the coin or token operated levers, by means of which the raising of the locking-bar from the locking-wheel and the unlocking of the latter are effected; Fig. 8, a transverse section taken in the plane yy

of Fig. 2 looking downward and showing the ratchet and pawl and the pulley and flexible connection through which the rotation of the passage-way-closing device may be effected 5 by the foot of the operator through the pedal shown in Fig. 1; and Fig. 9, a transverse sectional elevation of the slots or channel-ways through which the coins or other tokens are passed into the machine to effect the unlock- 10 ing of the passage-way-closing device and the receptacles for receiving them after having effected such unlocking operation.

In all the figures like letters of reference are employed to designate corresponding 15 parts.

A indicates one of the walls of a passage-way, with which co-operates a closing device that is adapted to be extended across the way to obstruct the same and be wholly or partially 20 swung therefrom when desired to allow of the passage of persons along the way or otherwise. This closing device may be constructed in various forms—as, for instance, in that of a door, a gate, a folding blind, or 25 other approved structure. As here shown, however, it is constructed in the form of a turnstile, which is preferably, though not necessarily, located near the wall of the passage-way opposite the wall A and consists of a 30 supporting shaft or axis B, which is journaled in the easing or housing C and is provided with a series of radially-disposed arms d d, formed by the angular bars D, that are jointed therein at right angles to each other with a 35 hollow cylinder or sleeve E surrounding it, which, fixedly secured to the upper side of the easing or housing C by bolts or otherwise, is provided at its upper end with a cam-surface e for extending and withdrawing the arms 40 when the turnstile is rotated, all as is common to the construction shown in the application for Letters Patent aforesaid and requires no further description herein.

For locking the closing device in a position 45 to obstruct the passage-way various means may be employed. I prefer, however, to make use of the wheel F, which is provided in its upper surface, near the periphery thereof, with a series of notches f, that receive and co-oper- 50 ate with the lower end of a locking-bar G, which in turn is fitted to slide in a suitable bearing or socket g, supported from the under side of the top of the easing or housing C by bracket-arms g' or otherwise, as preferred.

55 In some instances I find it convenient to locate the locking-wheel F on the shaft or axis of the closing device, in which cases it will be fixedly secured thereto. In my preferred form of construction, however, it is located 60 upon a shaft H, which is journaled in the easing or housing C and is connected with the shaft or axis B through the medium of gears h and h', the diameter of the former of which in the example of the invention shown is one- 65 fourth of that of the latter, whereby one complete rotation of the smaller of the two gears

will rotate the larger through one-quarter of its circumference or through an angle of ninety degrees. By this arrangement of parts and proportioning of the gears, as will be seen, 70 not only is the holding of the closing device when in a locked position firmly accomplished, but whatever strain there may be communicated to the locking-bar therefrom is reduced to the minimum.

75 The means made use of by me, through which the unlocking of the closing device may be effected when it is desired to withdraw the same from across the passage-way, is of the coin or token operated class and may be modified in various ways. By the terms "coin or token" used herein it is meant to include not only "coins" properly so called, but any other body that will be of the proper weight, size, or shape to effect the desired unlocking 80 operation when introduced into the machine, and the form of mechanism upon which it is designed to operate selected by me for the exemplification of my invention comprises a lever I, which, fulcrumed at the appropriate 85 point along its length in a suitable stand i, secured to the easing or housing C, is connected at one of its ends with the upper end of the locking-bar G through an orifice g², formed therein, with its opposite end extend- 90 ed into and wholly or partially across a slot or channel-way k, formed in a casing K, that extends downward through the top of the housing C and depends from the under side thereof, as shown. As thus arranged, the introduction of a coin or token into the channel-way k will cause the depression of the end of the lever I that extends into the latter by its contact therewith, with the consequent elevation of the other end of the same and 95 through it the raising of the locking-bar G from engagement with the notches f in the wheel F, thereby unlocking the closing device 100 and permitting of the movement of the same about its axis, as desired. The coin or token 105 having thus tilted the lever I upon its fulcrum will pass down the channel-way k and be deposited in an appropriate receptacle k³, arranged to receive it, when the lever, relieved from the action of the same, will, with 110 the locking-bar, under the action of gravity of the latter or otherwise return to its normal position, again locking the closing device 115 in a position across the passage-way, and be ready for the next operation, and so on. 120

In the construction of the wheel F, I sometimes find it convenient to provide it with only such notches f as are actually necessary to lock the closing device in the various positions it will occupy when obstructing the 125 passage-way, and in such cases these notches will be so located therein as to bring one or the other of them directly beneath the locking-bar G as the successive arms or barriers of the device are brought across the passage-way. At other times I find it convenient to provide this wheel with a continuous series 130

of such notches, as shown, for instance, in Figs. 2, 3, and 4, and this is the construction I prefer in practice, as thereby the locking of the closing device is insured even when the 5 obstructing portion of the closing device is by accident or otherwise carried slightly beyond a line extending from its axis perpendicularly across the passage-way. With this construction, however, the engagement of the locking-bar G with the notches f would in most cases result before the closing device in its movement had arrived in position to obstruct the passage-way if provision was not made to prevent such occurrence, as the coin or token introduced in the slot or channel-way k passes downward quickly therethrough into the receptacle k³ and, after having tilted the lever I on its fulcrum by contact therewith and raised the locking-bar G from the notches f, 10 allows these parts to rapidly return in the opposite direction toward their normal positions. In order, therefore, to prevent the engagement of the locking-bar with the notches in the wheel F during this return movement 15 before the closing device has arrived at the required position to obstruct the passage-way, various forms of mechanism may be employed. I prefer, however, to make use of a guard or baffle lever L, which, fulcrumed near its mid-20 dle point in a suitable hanger l, that is secured to the casing or housing C, is arranged with its flattened free end in close relationship to the locking-bar G, whereby to be passed under the lower end of the same when the 25 bar is raised and prevent it from engaging with the notches f in the wheel F while such end is there disposed. For swinging this guard or baffle lever on its fulcrum to carry its flattened free end beneath the locking-bar G 30 when required, I preferably, though not necessarily, avail of a lever m, which, fulcrumed at the proper point along its length in a suitable stand m³, that is secured to the casing or housing C, is jointed at its lower end with the 35 rear end of such guard or baffle lever and is provided at or near its upper end with an inclined surface m⁴, that is adapted to bear against the side of the lever I, as shown. By 40 this arrangement, as will be seen, the arm of the lever I that extends into the channel-way k as it is depressed by the action of the coin or token introduced into the latter will, as its other arm raises the locking-bar G from the notches f in the wheel F, move down along 45 this inclined surface m⁴, thereby swinging the lever m over on its fulcrum and through its connection with the guard or baffle lever L cause the passage of the flattened free end of the last-mentioned lever beneath the 50 locking-bar G, in which positions the locking-bar and the levers L and m will remain until the flattened free end of the lever L is removed from beneath the locking-bar, when the parts will return to their initial positions ready for the next operation, and so on. 55 The locking-bar G being thus raised from the notches f and held from engagement there-

with by the interposed flattened end of the guard or baffle lever L, the movement of the closing device around its axis to successively open and close the passage-way is permitted, and in order to insure of its being arrested in its movement and yieldingly held in position to obstruct the passage-way after each withdrawal therefrom I make use of the cam M, 70 which, preferably secured to the axis of the closing device and constructed with as many projections and depressions on and in its periphery as there are arms or barriers carried by the closing device, coöperates with the roller m⁵, that is journaled in the forked end of a rod m⁶, which, fitted to slide in a socket formed in a stand m⁷, secured to the casing or housing C, is held pressed outward with the roller m⁵ against the cam M by spring- 75 pressure, as shown. By thus arranging the depressions in the cam in proper position with respect to the arms or barriers of the closing device and the roller m⁵ the movement of such device to a position to obstruct the passage-way will be normally effected whenever it has been wholly or partially withdrawn therefrom, and to the end that the closing device may be automatically locked in this position when returned thereto I provide the upper 80 side of the gear h' with a number of upwardly-projecting studs h², which are so disposed with respect to the arms or barriers of the closing device and an extension l' on the flattened free end of the guard or baffle lever L 85 that when such closing device in its movement reaches a position to obstruct the passage-way, or nearly so, one of these studs h² will engage with the extension l', carrying the free end of the lever L from under the locking-bar G and allowing such bar to engage 90 with one of the notches f in the wheel F, thereby locking the closing device and returning the parts to their normal positions 95 ready for the next operation. 100

In some locations where the coins or tokens of but one denomination or character will be employed only a single slot or channel-way k, with a single coöperating receptacle k³, lever I, and lever m, will be required. In other locations where coins or tokens of different denominations or characters are employed, on the other hand, it will be found convenient 105 to employ a separate channel-way k' k' k³, &c., for each, with a separate coöperating receptacle k' k⁴ k⁵, &c., a separate coöperating lever I' I², &c., and a separate coöperating lever m' m², &c., as thereby the different denominations or characters of coins or tokens may be kept separate and distinct from one 110 another to denote different objects or purposes, and in practice I contemplate so employing them. While thus a plurality of levers I' I², &c., are employed when a plurality of channel-ways k' k², &c., are made 115 use of, the said levers are all preferably connected with the single locking-bar G, and the same is true with the levers m' m², &c., when a plurality is employed, such levers be- 120 125 130 135

ing severally connected at their lower ends with the single guard or baffle lever L, as shown.

With the parts above described I sometimes find it convenient to employ a registering device N to register the number of times the closing device has been withdrawn from across the passage-way to permit of the passing of a person therethrough or otherwise.

10 This registering device may be of any of the well-known or approved forms and located at any convenient point with respect to the closing device. In the drawings, however, I have shown it as located within the casing or housing C, and this is the location I prefer. When thus located, I preferably operate it from the shaft H through the intervention of the bevel-gears n and n' and the shaft n^2 , which shaft is supported in a suitable stand n^3 , secured 15 to the floor of the casing or housing C or other convenient part, as preferred. As thus constructed and arranged the locking and controlling mechanism for the closing device may be located in any convenient or desired 20 relationship with respect to the passage-way. I prefer, however, to so locate the same that the outer side of the casing or housing C may form one wall of the passage-way, as the part A forms the other wall thereof.

25 With the parts constructed and arranged as above described the unlocking of the closing device by the deposition of a coin or token and the withdrawal of the same from across the passage-way may be effected by the person who passes along the latter. It is preferred, however, to employ a second person therefor, who may be either the ticket-seller, transfer agent, or other person specially employed for the purpose, who, in addition to depositing 30 the coin or token in the appropriate slot or channel-way, and thereby unlocking the closing device, may also operate such closing device to withdraw it from and extend it across the passage-way, and for this purpose either 35 a crank N' or a pedal O may be adopted. When a crank is availed of for effecting the result, I preferably apply it to the upper end of the shaft H. On the other hand, when a pedal is employed I find it convenient to construct it in the form of a bell-crank, which is 40 preferably pivoted to the side of the casing or housing C and connected with the shaft or axis B through the intervention of a wheel o, a ratchet o', pawl o², a cord or strap o³, and 45 a spring o⁴, as shown, of which devices the wheel is loose upon the shaft or axis and the ratchet fast thereon.

50 From the foregoing it will be seen that I produce a simple and convenient means for locking and controlling the movements of a 55 passage-way-closing device which is adapted for use in cars, steamboats, railway-stations, theaters, and other similar locations, either to control the entrance thereto or the exit 60 thereof.

Although in the above I have described certain of the ways in which my invention is

or may be carried into effect, I wish it distinctly understood that I do not limit myself thereto, as it is obvious that the same may be modified in various other ways without departing from the spirit thereof.

Having thus described my invention, I claim and desire to secure by Letters Patent of the United States—

75

1. The combination with a passage-way-closing device adapted to be extended across such passage-way and withdrawn therefrom, of devices for positively locking it in its extended position, devices operable by the deposition of a coin or token to actuate said locking devices and release the said closing device, and means to hold said locking devices in inoperative position during the movement of the closing device from and across the passage-way.

80

2. The combination with a passage-way-closing device adapted to be extended across such passage-way and withdrawn therefrom, of devices for locking said closing device in its extended position, a lever adapted to be moved by the deposition of a coin or token to actuate said locking devices and release said closing device, and means actuated by said coin-operated lever to hold said locking means in inoperative position during the movement of the closing device from and across the passage-way.

85

3. The combination with a passage-way-closing device adapted to be extended across such passage-way and withdrawn therefrom, of devices for positively locking said closing device in its extended position, a coin or token operated lever to actuate said locking devices and release said closing device, and a second lever operated by said coin-operated lever to hold said locking devices in inoperative position during the movement of the closing device from and across the passage-way.

90

4. The combination with a passage-way-closing device, adapted to be extended across such passage-way and withdrawn therefrom, of devices for positively locking said closing device in its extended position, a coin or token operated lever to actuate said locking devices and release said closing device, a second lever operated by said coin-operated lever to hold said locking devices in inoperative position during the movement of such closing device from and across such passage-way, and means for automatically throwing said second lever to allow the locking devices to resume their operative position.

110

5. The combination, with a passage-way-closing device, and a wheel connected therewith and provided with notches, of a locking-bar adapted to engage with such notches to positively lock the closing device in a predetermined position, a lever adapted to be operated by a coin or token for disengaging the locking-bar from such notches, a guard or baffle lever, and a third lever for forcing the free end of this guard or baffle lever beneath the locking-bar when raised operated by the

115

120

125

130

135

tilting of the first-mentioned lever, substantially as described.

6. The combination, with a passage-way-closing device, and devices for positively locking it in a predetermined position, of a plurality of channel-ways for the reception of coins or tokens, and mechanism through which the unlocking of the closing device may be effected by the introduction of a coin or token in any one of the channel-ways, substantially as described.

7. The combination, with a passage-way-closing device, a wheel connected therewith and provided with a series of notches, and a locking-bar adapted to engage with such notches, of a plurality of slots or channel-ways that are each adapted to receive a coin or token, and a lever for coöperating with each of these slots or channel-ways and connected with the locking-bar, whereby the disengagement of the locking-bar from the notches in said wheel and the consequent unlocking of the closing device is effected by the introduction of a coin or token in any one of the slots or channel-ways, substantially as described.

8. The combination, with a passage-way-closing device, a wheel connected therewith and provided with a series of notches, and a locking-bar adapted to engage with such notches, of a plurality of slots or channel-ways that are each adapted to receive a coin or token of a different character, a lever for coöperating with each of these slots or channel-ways and connected with the locking-bar, whereby the disengagement of the locking-bar from the notches in said wheel and the consequent unlocking of the closing device is effected by the introduction of an appropriate coin or token in any one of the slots or channel-ways, and a receptacle for each of such slots or channel-ways arranged in proper re-

lation to receive the coin or token passed downward through the same, substantially as described.

9. The combination, with a wheel provided with notches in its upper side, a locking-bar adapted to engage with such notches, and a guard or baffle lever, of a plurality of slots or channel-ways that are each adapted to receive a coin or token of a different character, a lever coöperating with each of these slots or channel-ways and connected with the locking-bar, whereby the disengagement of such locking-bar from the notches of said wheel may be effected by the introduction of an appropriate coin or token in any one of the slots or channel-ways, and intermediate levers operated by the last-mentioned levers when tilted and connected with the guard or baffle lever to operate the same and force its free end beneath the locking-bar when raised, substantially as described.

10. The combination with a passage-way-closing device, of mechanism for positively locking said closing device in position to obstruct such passage-way; devices operable by the deposition of a coin or token to actuate said locking mechanism and release the closing device, automatically-operated devices for holding said locking mechanism in inoperative position during the movement of the closing device from and across the passage-way, and means for withdrawing said closing device from across the passage-way during the inoperative condition of said locking mechanism.

In witness whereof I have hereunto set my hand this 14th day of December, 1899.
